UNITED STATES PATENT OFFICE.

LEON F. HOFFMAN, OF FRANKLIN, PENNSYLVANIA, ASSIGNOR TO CHICAGO PNEUMATIC TOOL COMPANY, OF NEW YORK, N. Y., A CORPORATION OF NEW JERSEY.

ELECTROTHERMAL IGNITION DEVICE.

Application filed September 18, 1922. Serial No. 588,933.

To all whom it may concern:

Be it known that I, LEON F. HOFFMAN, citizen of the United States, residing at Franklin, in the county of Venango and State of Pennsylvania, have invented certain new and useful Improvements in Electrothermal Ignition Devices, of which the following is a specification.

The object, construction, application and utility of my improved electro-thermal ignition device are herein set forth with sufficient clearness to enable others skilled in the arts to which its construction and use respectively relate, to make and use the same.

My improved ignition device is especially adapted for use with heavy oil engines, of that type which after being in operation for a short time ignite their charge by high compression and the high degree of heat of certain portions of the wall of the combustion chamber. Supplementary ignition means are, however, necessary when starting such engines and the object of this invention is, primarily, to supply such supplementary means.

The construction and application of my improved ignition device are clearly shown in the accompanying drawings in which:

Fig. 1 is a central, longitudinal section of my improved device.

Fig. 2 is an elevation partly in central longitudinal section.

Fig. 3 is an elevation.

Fig. 4 shows said device applied to the combustion chamber of a well-known type of heavy oil engine.

Referring to said drawings, my improved ignition device comprises a spirally wound resistor coil 1 which is coiled around an insulator core, which, as shown in the drawing for the purpose of ready assembly, consists of two aligned sections 2 and 3. Passing centrally, longitudinally through said insulator is a conductor rod 4 which, at its projecting outer end is provided with lock-nuts 5 and 6, between which a suitable electrical conductor may be secured to supply current from any suitable source to the coils. The opposite, inner end of said conductor rod projects from said core 2-3. One end of the wire forming said resistor coil 1 is connected to said inner end of said conductor rod so as to supply current thereto—see Fig. 1. Said coil 1 is enclosed within a tube 7 of suitable metal, as nickel alloy, and

is held in position by that portion 8 of the organization which is termed the tube-holder. Said tube-holder is, itself, of substantially tubular shape, near the inner end of which is formed an annular, inwardly extending shoulder 9 which engages a co-operating, outwardly-projecting annular ring 10, upon the periphery of the open end of said tube.

The outer portion of said tube-holder is internally threaded for the reception of the co-operatively threaded element 11 which is termed the body, the inner end of which contacts with the adjacent end of said tube, thus firmly securing same in position.

The outer end of said body 11 is formed into a socket for the reception of an annular enlargement 12 of the insulating core. Said socket 12 is internally screw-threaded for the reception of a co-operatively, externally-threaded thimble 13, the inner end of which bears upon the outer face of said annular enlargement 12, thus firmly securing said insulating core firmly in position. The inner end of said tube-holder is externally screw-threaded for insertion into a tapped hole through the wall of the combustion chamber 14 of an oil engine.

It has been previously pointed out that one end of the wire forming the resistor coil 1 is connected to the inner end of the conductor rod 4. It is now explained that the other end of said wire is connected to the body 11, thus grounding the coil through the engine.

When an electrical current is caused to flow through the resistor 1 the same becomes incandescent, and the resulting heat is imparted to the tube 7, causing it also to become incandescent, and thus suitably heated to ignite the fuel mixture in the combustion chamber of the engine in which it is inserted.

I claim the following:

1. An electro-thermal ignition device for internal combustion motors, comprising a tubular casing closed at its inner end, a core of insulating material extending centrally into said casing and provided with a spirally disposed groove upon its periphery, a resistor composed of spirally-wound wire occupying said groove, a holder for said tubular casing, a tubular body through which said core extends, said holder and said body forming co-operative assembly means

for said casing and said core, and an electrical conductor extending through said core, to the inner end of which one end of said resistor is attached, the other end of said 5 resistor being attached to said holder.

2. An electro-thermal ignition device for internal combustion motors comprising in combination a tubular casing of nickel alloy, closed at one end and open at the other end, 10 the periphery of said open end being provided with an annular shoulder, a core of insulating material provided with a spirally-grooved periphery extending into said casing, a resistor carried by said insulator comprising a closely spirally-wound wire occupying the spiral grooves of said insulator, a holder for said tubular casing adapted to engage said annular shoulder, a tubular body through which said insulative core ex-

tends, said holder and said body forming co- 20 engaging assembly means for retaining said casing and said core in their proper relative positions, and an electrical conductor extending through said insulative core, said resistor having one of its ends connected to the inner end of said conductor, the other end of said resistor being connected to said holder and thus grounded, said holder being adapted for mounting said casing within the combustion chamber of an internal combustion 25 engine.

In testimony whereof I affix my signature in presence of two witnesses.

LEON F. HOFFMAN.
